UNITED STATES PATENT OFFICE.

RUDOLPH KYFES, OF LOCUST RIDGE, LOUISIANA.

GATE.

Application filed April 19, 1926. Serial No. 103,120.

This invention relates to gates adapted to open and close by the weight of a vehicle upon the inclines leading to and from the same.

5 An object of the invention is to relatively associate weight bars with the inclines to automatically close the gates after a vehicle has passed over the inclines.

With the above and other objects in view, 10 the invention further includes the following novel features and details of construction, to be hereinafter more fully described, illustrated in the accompanying drawings and pointed out in the appended claim.

15 In the drawings:—

Figure 1 is an elevation of the gate when closed;

Figure 2 is a similar view of the same when opened;

20 Figure 3 is a sectional view taken on the line 3—3 of Figure 1; and

Figure 4 is a transverse section taken through the operating arm for the gates.

Referring to the drawing in detail, where- 25 in like characters of reference denote cor- responding parts, the reference character 10 indicates an operating arm or beam fitted between the corresponding inner sides of gate posts 11 and bracket member 12 to insure proper movement of the beam 10 there- 30 in. A cross beam 13 has its opposite ends secured to the gate posts 11. Uprights 14 are positioned at spaced intervals along the length and upon the opposite sides of the 35 cross beam 13, the purpose of which will be readily apparent.

Pivotaly mounted upon the inner sides of the gate posts 11 are lazy tong gates 15 having their upper ends correspondingly se- 40 cured to rocking levers 16 operable by shafts 17 connected with the beam 10. The upper ends of the posts 11 provide bifurcated por- 45 tions within which are eccentrically mounted inwardly extending bars 18 having weights 19 positioned upon the innermost ends there- 50 of in a manner as clearly illustrated in Figure 1 of the drawings. Spaced inclines 20 have their corresponding meeting side edges hingedly associated upon the upper

The undersides of such inclines adjacent the outer edges thereof provide roller mem- bers 21 thereon operable within race-ways, not shown, provided in inclined abutments 22 to protect such edges of the inclines and to insure the proper operation thereof.

In the use and operation of the present invention it is clearly apparent and mani- 45 fest that a vehicle approaching the gate upon either of the inclines 20 will depress the beam 10 in the position as illustrated in Figure 2 of the drawings which action im- parts a downward pull upon the shafts 17 to rock the levers 16 and simultaneously fold the lazy tong gates 15 upon themselves 55 behind the uprights 14.

The bars 18 during such operation are raised slightly above the beam 13 and sub- sequently to the passing of the vehicle through the gate the weights 19 carried 70 thereon, will automatically raise the shafts 17 and beam 10 and simultaneously operate the rock levers 16 to close and move the gates 15 to their normal inactive positions 75 as illustrated in Figure 1 of the drawings.

The invention is susceptible of various changes in its form, proportions and minor details of construction, and the right is here- 80 in reserved to make such changes as properly fall within the scope of the appended claim.

Having thus described my invention what I claim is:

A gate structure comprising pivotally mounted lazy tong gates, posts, rock levers mounted upon the posts and connected with 85 the lazy tong gates, an operating beam ex- tending longitudinally of the gates, inclines leading to and hingedly mounted upon the operating beam, shafts connecting the free 90 ends of the beam and rock shafts; and weight bars eccentrically mounted upon the upper ends of the posts and connected with the shafts to facilitate an automatic closing mechanism for the gates subsequent to the 95 passing of the vehicle therethrough.

In testimony whereof I affix my signa- ture.

RUDOLPH KYFES.
